UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

GUN FOR ACCOMPANYING ATTACKING TROOPS.

1,346,562.

Specification of Letters Patent.

Patented July 13, 1920.

Application filed February 28, 1920. Serial No. 362,114.

To all whom it may concern:

Be it known that I, EUGÈNE SCHNEIDER, of Paris, France, have invented new and useful Improvements in Guns for Accompanying Attacking Troops, which invention is fully set forth in the following specification.

The present invention has for its object to provide an improved construction of the gun designed for accompanying attacking troops for which a patent was applied for on 24th October, 1919; Serial Number 333,103. The present invention also consists in various improvements in the said gun.

Examples of the said improved construction and of the said improvements are illustrated in detail in the accompanying drawings in which:

Complementary Figures 1 and 1^a are a side elevation of the improved gun according to the present invention.

Complementary Figs. 2 and 2^a are a corresponding plan showing the shaft-like trails.

Complementary Figs. 3 and 3^a are a side elevation drawn to a larger scale, partly in section on the line 1—1 of Figs. 4 and 4^a, various parts being broken away to show the constructional details of the gun.

Complementary Figs. 4 and 4^a are a corresponding partial horizontal section.

Complementary Figs. 5 and 5^a are a rear end elevation of the gun, the barrel-like casing for supporting the gun carriage being shown in cross section on the line 3—3 of Fig. 3.

Figs. 6 and 7 are partial detail vertical sections showing in two different positions the apparatus for operating flaps in the shell of the casing that are turned down for firing and turned up when the gun is to be transported.

Fig. 8 is a sectional elevation illustrating the mounting of the bracket carrying the sighting apparatus on one of the trunnions of the barrel-like gun carriage casing, and the mechanical connection between the sighting apparatus proper and the gun cradle.

Fig. 9 is a diagram showing respectively in full lines and in dot and dash lines, two different positions of the combined barrel-like gun carriage casing and shaft-like

trails for two different firing elevations of the gun.

Fig. 10 is a diagrammatic elevation illustrating the maneuver of running the gun back into battery position in case of a misfire.

In the same manner as in the constructional forms described in our aforesaid application for patent, the gun is completely inclosed in a barrel-like casing A closed at two ends B, B¹ and provided in its axis with two trunnions F, F¹. On each of these trunnions there is mounted loosely a collar G, G¹ provided with a truncated conical sleeve g, g¹ for the engagement of the correspondingly shaped ends of the shaft-like trails, for transporting the gun.

The gun barrel E is carried by a cradle C engaged at its rear end by means of a sleeve e on a pivot pin d fixed to a metal plate D forming part of the casing A and of the internal sheet metal supports D¹.

D², D³ are reinforcing plates which may be arranged symmetrically with relation to the plate D on the one hand and the plates D¹ on the other hand.

The cradle C engages with its front part a guide D⁴ of arc shape centered at the axle pin d and fixed to the plate D. An operating mechanism of any known suitable construction allows of turning the combined cradle and gun barrel on the pivot d. This mechanism comprises for instance a shaft U as shown in the drawings, journaled in the cradle C, on the forward end of which there is fixed a helical wheel U¹. This wheel meshes with a helical wheel U² fixed on a shaft U³ that carries a worm U⁴. The latter meshes with helical teeth formed on an arc D⁵ that may be fixed to the guide D⁴, and is centered on the pivot pin d. Rotational motion can be imparted to the shaft U by means of a crank handle u.

The hub of the crank handle carries a spur u¹ movable in a slot u² in the shaft U. According as the spur u¹ is moved right up to the front or right up to the back of the slot u², the crank handle can be caused to disappear inside the casing A for transport, or it is withdrawn from the casing, for training the gun after the flaps A¹, A², have been let down.

The training mechanism just described does not comprise any particular character-

istic feature other than the arrangement for causing the crank handle or the hand wheel to disappear into the casing.

In the example described, the improved gun comprises two recoil brakes E^1 of any known type, of which E^1 are the cylinders moving with the gun barrel E in the recoil. E^2 are the brake piston rods fixed to the cradle C . E^3 are springs arranged around 10 the brake cylinders E^1 ; they are compressed by the recoil and their expansion serves to return the gun into battery position again.

One of the characteristic features of the improved gun consists in the particular construction of the shaft-like trails for the purpose of providing a simple mechanism for elevating the gun barrel.

For this purpose the trails each of which is pivotable at its rear end h^1 on a pin i carried by an anchoring device I , are adapted to be simultaneously shortened or lengthened by the same amount by means of a common actuating mechanism.

In the example shown, this mechanism 25 comprises for each trail (composed of two sections H^1 , H^2) a tensioning device, such as a rod with right and left handed screw threads K^1 , K^2 engaging in corresponding internal screwthreads formed in the tubular sections H^1 , H^2 . One of these tensioning devices, for instance the left hand one, has fixed on it an operating member L . The transmission or gearing connecting the two tensioning devices K^1 , K^2 , may for instance 35 be constructed as shown in detail in Figs. 2 and 2^a. The screw-threaded elements K^2 are tubular and the rear end of each serves as a guide for a square element h^3 of a shaft K^3 which is journaled at its rear end in a bearing 40 provided in the trail section H^2 . Each of the shafts K^3 carries a bevel pinion K^4 meshing with a pinion K^5 carried by a pin h^5 likewise journaled in a bearing in the respective section H^2 . The pins h^5 are in 45 line with each other and are operatively connected together by a sleeve K^6 . The latter thus constitutes one of the elements of the transmission connecting the two tension devices, while it can also serve as a push 50 bar for the trails during transport.

The lengthening or shortening of the trails H^1 , H^2 is produced as already described, by actuating in the desired direction the member L so as to move the sections H^1 away from or nearer to the sections H^2 .

For the purpose of assuring the rigidity of the combination, during both firing and transport, a staying arrangement may be provided between the sections H^2 , consisting 60 of rods h^2 pivoted on the said sections H^2 , these rods being connected if desired at one end by means of an assembling pin h^8 . The rods h^2 may, like the bar K^6 , be adapted to be folded against the sides of the shaft-like 65 trails as indicated in dot and dash lines in

Fig. 2^a. This folding may become necessary either in the case of the gun being drawn by a horse or a mule, or in the case where it is desired to dismount the shaft-like trails for the purpose of transport. Even when the 70 gun has been brought up to the firing line, it may be necessary to dismount the shaft-like trails, in order to use them as a bridge for the transport of the gun when it is required to move the latter over a ditch or a trench. 75

The diagrammatic Fig. 9 shows how a simultaneous shortening of the shaft-like trails by a given amount enables the gun barrel with its accessories or the gun cradle with its accessories to be elevated through an 80 angle α . It is evident that the shortening of the trails, starting from the position shown in full lines in this figure, will have the effect of causing the casing A on coming in contact with the ground to roll over 85 it, around the axis of the trunnions F . This casing in rolling along the ground will move through a distance x , carrying with it the gun E . This will produce an elevation of 90 the gun through an angle α ; the arc of this angle, measured along the central circle of the casing A , is a development of the distance x traversed by a point of the said circle along a line tangential to the latter.

For the purpose of affording rigidity during firing, the improved gun is provided with tie-rods N for connecting the sections H^2 to the ends B , B^1 of the barrel-like casing. These tie rods N which may be hinged up to the trails during transport, may be 100 left in position during the alteration of the elevation, if the position of their pivotal connection to the barrel-like casing is suitably chosen.

Another improvement of this invention 105 consists in a mechanism for actuating the flaps A^1 , A^2 , for the purpose of opening them when the gun is run into battery position, and for locking them for transport on a vehicle for rolling along the ground. 110

As shown in detail in Figs. 6 and 7 each of these flaps is pivoted at one of its longitudinal edges by means of two hinges a^1 to the casing A . It is formed on its opposite edge with two sockets a^2 for engagement 115 with an axle pin J , which is half cut away at j along a length equal to the said sockets a^2 .

When by the rotation of the axle J produced as hereinafter described, the said axle 120 is moved into the position shown in Fig. 7 the sockets a^2 which were engaged on the said axle are now free so that the flaps are able to fall down by their own weight or by the action of a returning spring. The 125 engagement of the flaps is done while the axle is in the same position (Fig. 7) the flaps being of course raised by hand into their closed position shown in Fig. 6. Their locking is assured immediately the axles J 130

have been turned to bring them into the position shown in the said Fig. 6.

The bearings for the axles J may be formed on brackets J^1 fixed to the inside 5 wall of the casing A . These brackets may preferably be arranged to project from a frame J^2 serving as a rest for the edge of the flap A^1 in its closed position; the said frame being provided for this purpose with 10 a rubber packing j^2 . By this means a perfectly tight closure of the casing is produced which allows of transporting a gun across rivers by floating the gun carriage casing.

15 The simultaneous actuation of the two axles J for opening the flaps A^1, A^2 , may be effected as shown in the drawings.

On each of the axles J there is fixed a toothed wheel J^3 connected by a chain J^4 to 20 a corresponding toothed wheel J^5 fixed on a shaft J^6 for which a bearing is formed by one of the trunnions F^1 of the barrel-shaped casing A . The outer end of the shaft J^6 is provided with an operating hand wheel j^6 . 25 This hand wheel j^6 may be locked by a bolt.

The improved gun is further characterized by a peculiar mounting of the bracket for the sighting apparatus upon one of the trunnions of the casing, and a connection 30 between the sighting apparatus proper, movable in said bracket, and the gun carriage cradle.

This mounting is shown more particularly in Figs. 4 and 8.

35 The bracket M for the sighting apparatus has two ribs m downwardly converging for engaging in corresponding guide grooves formed in the outer end of the trunnion F . In this bracket M there is journaled a screw 40 M^1 provided with a tenon m^1 formed with flats and which when the bracket M is engaged in the trunnion F , fits in the end of a sleeve O capable of turning in the trunnion F . This sleeve is formed on its inside 45 wall with a helical groove o of varying pitch in which engages a tenon p projecting from a rod P engaged in the sleeve O . The lower end of this rod is pivoted at p^1 to the cradle C .

50 It will be readily understood that at each movement of the cradle C by means of the training mechanism operated by the crank handle u , there corresponds an angular movement of the sleeve O carrying the screw M^1 around with it. The sighting apparatus proper Q is movable in the bracket M and is formed on its supporting stem q with helical teeth q^1 meshing with the worm M^1 .

55 By suitably shaping the helical groove o , the sighting apparatus proper Q may be given angular displacements that are identically the same as those given to the combined cradle and gun barrel around the axis of the trunnion d .

60 The gun may be constructed in the known

manner which allows of locking the gun barrel during its recoil and unlocking it at the time of firing. In this case as is well known there is produced a movement of the gun barrel in the forward direction relatively to the gun carriage, and this displacement diminishes the velocity of recoil by a corresponding amount. It is to be understood that the recuperators are suitably constructed for this purpose.

75 In a gun of that kind, in the case of a misfire, that is to say, when the firing of the gun has not produced an explosion of the charge, it is necessary to return the gun barrel into battery position.

80 According to this invention a simple device is provided for effecting this rearward movement of the gun barrel.

85 The gun barrel is provided with a fastening device such as an eye or ring e (Fig. 3^a) for one of the ends of a rope R which passes over a pulley S movable on an axle s that is carried for instance by a block h^4 fixed to the pin h^5 (Fig. 1^a). The other end of this rope can be attached to a ring a^3 provided on the casing A .

90 The diagrammatic Fig. 10 shows in full lines the gun barrel E brought by the recuperators into position I and stopped in this position by reason of the non-operation 95 of the firing mechanism.

95 For the sake of simplicity it is assumed that the firing took place when the gun barrel was in a horizontal position, but that whatever its angle of firing may be, it is necessary for compressing the recuperator springs, to first bring the gun barrel by operating the elevating mechanism, to a determined elevation, say 20°, as indicated in dot and dash line in the same diagram (position II).

100 When this operation has been done, the rope R is attached in place and by means of the elevating mechanism the gun barrel is brought into the horizontal position III, indicated in dotted lines. In this movement the casing which occupied position II assumes position III, whereas the anchoring device remains stationary. Since the length 105 of the rope is constant the casing has moved forward while the gun barrel has been moved to the rear into the position in which it can be locked for loading. In this position the rope can be removed, and the firing operations resumed.

110 In the improved construction, the casing A is provided with a rolling tread T of rubber, leather or any other suitable material.

115 What I claim is:

120 1. In a gun mount, the combination of a barrel-shaped casing adapted to roll on the ground for transportation and having in its periphery diametrically opposite openings, a gun mounted in the casing in line with 125 said openings, and flaps for closing said 130

openings to complete the periphery of the casing for rolling on the ground during transportation.

2. In a gun mount, the combination of a barrel-shaped casing adapted to roll on the ground for transportation and having in its periphery diametrically opposite openings, a gun mounted in the casing in line with said openings, flaps for closing said openings to complete the periphery of the casing for rolling on the ground during transportation, and a tread extending around the periphery of the casing.

3. In a gun mount, the combination of a barrel-shaped casing adapted to roll on the ground for transportation and having in its periphery diametrically opposite openings, a gun mounted in the casing in line with said openings, flaps for closing said openings to complete the periphery of the casing for rolling on the ground during transportation, trunnions on the opposite ends of the casing in line with the axis thereof, and trails journaled on the trunnions available either for propelling the casing during transportation or for anchoring the gun during firing.

4. In a gun mount, the combination of a barrel-shaped casing adapted to roll on the ground for transportation and having in its periphery diametrically opposite openings, a gun mounted in the casing in line with said openings, flaps for closing said openings to complete the periphery of the casing for rolling on the ground during transportation, trunnions on the opposite ends of the casing in line with the axis thereof, longitudinally adjustable trails journaled at their front ends on the trunnions, means for anchoring the rear ends of the trails, and means for adjusting the length of the trails to roll the casing on the ground to vary the elevation of the gun.

5. In a gun mount, the combination of a barrel-shaped casing adapted to roll on the ground for transportation and having in its periphery diametrically opposite openings, a gun mounted in the casing in line with said openings, flaps for closing said openings to complete the periphery of the casing for rolling on the ground during transportation, trunnions on the opposite ends of the casing in line with the axis thereof, longitudinally adjustable trails journaled at their front ends on the trunnions, means for anchoring the rear ends of the trails, and operative mechanism common to both trails for simultaneously adjusting the length of the same to roll the casing on the ground to vary the elevation of the gun.

6. In a gun mount, the combination of a barrel-shaped casing adapted to roll on the ground for transportation and having in its periphery diametrically opposite openings, a gun mounted in the casing in line with

said openings, flaps for closing said openings to complete the periphery of the casing for rolling on the ground during transportation, trunnions on the opposite ends of the casing in line with the axis thereof, sectional trails journaled at their front ends on the trunnions, and means for anchoring the rear ends of the trails, the sections of each trail being connected by a rotatable element having oppositely screwthreaded engagements with the contiguous ends of the sections so that the turning of said element in one direction will lengthen the trail and in the opposite direction will shorten it, the lengthening and shortening of both trails operating to roll the casing on the ground to vary the elevation of the gun.

7. In a gun mount, the combination of a barrel-shaped casing adapted to roll on the ground for transportation and having in its periphery diametrically opposite openings, a gun mounted in the casing in line with said openings, flaps for closing said openings to complete the periphery of the casing for rolling on the ground during transportation, trunnions on the opposite ends of the casing in line with the axis thereof, sectional trails journaled at their front ends on the trunnions, and means for anchoring the rear ends of the trails, the sections of each trail being connected by a rotatable element having oppositely screwthreaded engagements with the contiguous ends of the sections so that the turning of said element in one direction will lengthen the trail and in the opposite direction will shorten it, the lengthening and shortening of both trails operating to roll the casing on the ground to vary the elevation of the gun, and means for simultaneously turning the rotatable elements of both trails to lengthen or to shorten simultaneously both trails.

8. In a gun mount, the combination of a barrel-shaped casing adapted to roll on the ground for transportation and having in its periphery diametrically opposite openings, a gun mounted in the casing in line with said openings, flaps for closing said openings to complete the periphery of the casing for rolling on the ground during transportation, trunnions on the opposite ends of the casing in line with the axis thereof, sectional trails journaled at their front ends on the trunnions, and means for anchoring the rear ends of the trails, the sections of each trail being connected by a rotatable element having oppositely screwthreaded engagements with the contiguous ends of the sections so that the turning of said element in one direction will lengthen the trail and in the opposite direction will shorten it, the lengthening and shortening of both trails operating to roll the casing on the ground to vary the elevation of the gun, means for turning the rotatable element of one trail,

- and means for transmitting the movement of the turning element to the rotatable element of the other trail to lengthen or to shorten simultaneously both trails.
- 5 9. In a gun mount, the combination of a barrel-shaped casing adapted to roll on the ground for transportation and having in its periphery diametrically opposite openings, a gun mounted in the casing in line with said openings, flaps for closing said openings to complete the periphery of the casing for rolling on the ground during transportation, trunnions on the opposite ends of the casing in line with the axis thereof, trails journalized on the trunnions available either for propelling the casing during transportation or for anchoring the gun during firing, and a displaceable frame comprising foldable members adjustable to connect the trails.
- 10 10. In a gun mount, the combination of a barrel-shaped casing adapted to roll on the ground for transportation and having in its periphery diametrically opposite openings, a gun mounted in the casing in line with said openings, flaps for closing said openings to complete the periphery of the casing for rolling on the ground during transportation, trunnions on the opposite ends of the casing in line with the axis thereof, trails journalized on the trunnions available either for propelling the casing during transportation or for anchoring the gun during firing, and a displaceable frame comprising foldable members adjustable to connect the trails.
- 15 11. In a gun mount, the combination of a barrel-shaped casing adapted to roll on the ground for transportation and having in its periphery diametrically opposite openings, a gun mounted in the casing in line with said openings, flaps for closing said openings to complete the periphery of the casing for rolling on the ground during transportation, trunnions on the opposite ends of the casing in line with the axis thereof, trails journalized on the trunnions available either for propelling the casing during transportation or for anchoring the gun during firing, and a displaceable frame comprising foldable members hinged to the trails and adjustable to form diagonal connections between the trails to hold them in fixed parallel arrangement.
- 20 12. In a gun mount, the combination of a barrel-shaped casing adapted to roll on the ground for transportation and having in its periphery diametrically opposite openings, a gun mounted in the casing in line with said openings, flaps for closing said openings to complete the periphery of the casing for rolling on the ground during transportation, a lock for each flap to secure the same in closed position during transportation.
- 25 13. In a gun mount, the combination of a barrel-shaped casing adapted to roll on the ground for transportation and having in its periphery diametrically opposite openings, a gun mounted in the casing in line with said openings, flaps for closing said openings to complete the periphery of the casing for rolling on the ground during transportation, trunnions on the opposite ends of the casing in line with the axis thereof, trails journalized on the trunnions available either for propelling the casing during transportation or for anchoring the gun during firing, and a displaceable frame comprising foldable members hinged to the trails and adjustable to form diagonal connections between the trails to hold them in fixed parallel arrangement.
- 30 14. In a gun mount, the combination of a barrel-shaped casing adapted to roll on the ground and having in its periphery diametrically opposite openings, a carriage carrying a gun mounted in the casing in line with said openings and pivoted therein for training the gun through one of said openings, trunnions on opposite ends of the casing in line with the axis thereof, trails journalized at their front ends on the trunnions, means for anchoring the rear ends of the trails, a bracket carrying sighting apparatus mounted on one of the trunnions, and mechanism for transmitting the training movement of the gun carriage through the trunnion carrying the bracket to the sighting apparatus on said bracket.
- 35 15. In a gun mount, the combination of a barrel-shaped casing adapted to roll on the ground and having in the periphery diametrically opposite openings, a gun and brake mechanism carried by a carriage mounted in the casing in line with said openings, said brake mechanism operating to move the gun forward on the carriage at the moment of firing, trunnions on the opposite ends of the casing in line with the axis thereof, extensible trails journalized at their front ends on the trunnions, means for anchoring the rear ends of the trails, and a rope connected at one end to the gun and at the other end to the casing and looped around a pulley carried by the rear end of the trails so that an extension of the trails will move the casing on the ground to rotate the same, the rotation of the casing exerting a pull on the rope to return the gun to battery position from firing position.
- 40 16. In testimony whereof I have signed this specification.
